T. A. BOTH

TWO-LIGHT PLUG

Filed June 13, 1924

UNITED STATES PATENT OFFICE.

TONJES A. BOTH, OF STRATFORD, CONNECTICUT, ASSIGNEE TO THE CONNECTICUT ELECTRIC MANUFACTURING COMPANY, OF BRIDGEPORT, CONNECTICUT, A CORPORATION OF CONNECTICUT.

TWO-LIGHT PLUG.

Application filed June 13, 1924. Serial No. 719,779.

This invention relates to a multiple light plug, specifically to a two light plug, and has for an object to provide an improved plug of this type which will be simple in construction, involving a minimum number of parts, and in which these parts are so arranged that they may be easily and quickly assembled.

With the foregoing and other objects in view, I have devised the construction illustrated in the accompanying drawing forming a part of this specification, similar reference characters being employed throughout the various figures to indicate corresponding elements. In this drawing,

Fig. 1 is a central longitudinal section through the device.

Fig. 2 is a longitudinal section substantially at right angles to that of Fig. 1.

Fig. 3 is a transverse section substantially on line 3—3 of Fig. 1.

Fig. 4 is a transverse section substantially on line 4—4 of Fig. 1, and

Fig. 5 is an end view of one branch of the body member, the view being substantially on line 5—5 of Fig. 1.

The device comprises a body member 10, preferably of molded insulating material such as a phenolic condensation product, and this body comprises three branches 11, 12 and 13. The branch 11 has a shoulder 14 about the entrance to a pocket 15 on which shoulder is seated one end of an externally threaded shell contact 16. This contact has at its inner end inturned lugs 17 and embraces an insulating element 18 which I term a button as it has a rounded end projecting through the outer end of the contact 16. This element is provided with a shoulder 19 adjacent its outer end which is engaged by a spun over flange 20 of the contact 16.

The branches 12 and 13 are each provided with a socket 21 in which are mounted threaded socket shells 22 and 23 to receive the threaded side contact of a lamp or plug. These shells are provided at their inner ends with inturned lugs 24 and 25 respectively for coacting with securing means for mounting these shells in the sockets. Also mounted in the sockets are central contacts 26 and 27 respectively.

The various contacts are electrically connected and mounted in the body member

as follows: Engaging the lugs 24 and 25 are conductors 28, these conductors being placed under the lugs 25 and over the lugs 24. In assembling, the shell 22 may be placed in its socket and the conductors 28 placed in position with one end resting on the lugs 24. The shell 16 is then placed against the shoulder 14 and screws 29 are passed through the lugs 17 of this shell, through suitable openings and the lugs 24 in the body member and are threaded into the conductors 28, as shown in Fig. 2. These screws securely mount the shell 16 and 22 in position in the body member. The shell 23 may now be inserted in the lateral branch 13 and its lugs 25 secured to the conductors 28 by screws 30 passing through these lugs and threaded into the conductors. It will, therefore, be apparent that all three of the threaded shells are electrically connected and securely mounted in the body member by means of the screws 29, 30 and the conductors 28.

The central contacts are independently mounted in the body member. A metal angle block 31 is mounted at the inner end of the pocket 15 and the central contacts 26 and 27 are secured to this block by screws 32 and 33 respectively which pass through suitable openings 34 and 35 in the body member. Thus these central contacts are securely mounted in position and are also electrically connected. The insulating plug or button 18 is now placed within the shell 16 and secured in position by passing screw 36 through the end thereof and threading it into the block 31. The head 37 of this screw forms a central contact at the end of the button and thus all three of the central contacts are electrically connected. The end of this button rests against the lugs 17 on the shell 16, and a small inturned flange 38 which may be provided if desired, and assists in holding the contact 16 against the end of the body. The outer ends of this shell 16 are then spun over the shoulder 19, as shown at 20, and the device is completed. This spun over end gives a finished appearance and prevents loosening of the button. It will be apparent that the branch 11 may be inserted in any standard lamp socket or socket receptacle, the contacts 16 and 37 engaging the contacts in the sockets, and as the threaded contacts are all electrically con-

ected as well as the central contacts, the branches 12 and 13 may be used for lamps or plugs having connection with suitable appliances. The entrance to the sockets 21 may 5 if desired be tapered as shown at 39 to facilitate insertion of the lamp or plug, and these branches may be provided with annular grooves 40 in their outer walls for the purpose of mounting shade or reflector holders.

10 Having thus set forth the nature of my invention, what I claim is:

1. In a two light plug a body member of molded insulating material having a pocket leading from one end thereof, a metal block 15 mounted in said pocket, an externally threaded shell contact having inturned lugs embracing the entrance to said pocket, a socket extending inwardly from the other end of the body, a threaded shell in said 20 socket having inturned lugs, screws connecting the lugs of said shells forming an electrical connection between them and operating to clamp the shells to the body, a central contact in the socket, a screw connecting 25 said central contact with the metal block, an insulating button embraced by the first mentioned shell and having a shoulder adjacent its outer end, said shell having a flange spun over said shoulder, and a screw 30 extending through said button connected to the metal block and forming a central contact at the end of the button.

2. In a two light plug an insulating body member, said body comprising three branches 35 two of which are provided with sockets, an internally threaded contact shell in each socket, an externally threaded contact shell carried by the other branch, inturned lugs at the inner ends of the threaded contacts, conductors engaging the lugs of the internally 40 threaded contacts, screws passing through

the lugs of said contacts and threaded into said conductors, the screws for one of said contacts also passing through the lugs of the externally threaded contact and forming an electrical connection therewith, and electrically connected central contacts for said threaded contacts. 45

3. In a device of the character described, 50 an insulating body member having three branches, one of said branches having a pocket leading from the end thereof and the other two branches having sockets, said body being provided with a cross wall separating the pocket from the sockets, a block mounted in the pocket, central contacts in the sockets, 55 securing screws passing through the central contacts and the cross wall and threaded into the block to clamp the contacts and the block to said wall, an externally threaded shell contact having an inwardly extending lug mounted about the entrance to said pocket, 60 an insulating button embraced by said contact, a central contact comprising a threaded bar extending through said button and 65 threaded into the block to clamp the button to the body, screw shell contacts mounted in the sockets and having inwardly extending lugs, conductors engaging with said lugs, 70 screws passing through the lugs of the externally threaded contact and one of the socket shell contacts and threaded into said conductors to clamp the contacts and the conductors to the body and form an electrical connection between said contacts and said 75 conductors, and screws passing through the lugs of the other socket shell contact and threaded into the conductors to secure this contact thereto. 80

In testimony whereof I affix my signature. 80
